TELEGRAPH TRANSMITTER

Albert H. Reiber, Evanston, Ill., assignor to Teletype Corporation, Chicago, Ill., a corporation of Delaware

Application September 26, 1938, Serial No. 231,617

26 Claims. (Cl. 178—17)

This invention relates to printing telegraph apparatus and more particularly to telegraph transmitters for the transmission of character identifying signals.

5 Transmission of character identifying signals in telegraph systems is frequently achieved in accordance with a control strip including control indicia formed in varying combinations either by manually or remotely operated apparatus. 10 Specifically, the control indicia may be in the form of transverse rows of perforations formed in a tape either by a keyboard perforator or by a signal controlled perforator which is commonly referred to as a reperforator. The tape thus 15 prepared passes through a transmitter or sensing mechanism to control correspondingly the transmission in succession of impulses identified with the perforations, which has its tape entrance channel separated from the tape exit channel 20 of the perforator under such conditions a short length of tape extends between the perforator and the transmitter and contains a group of perforations, for the last character perforated is not sensed unless the tape is advanced to present 25 such group of perforations to the transmitter or unless the sensing mechanism is made movable along the control strip to sense the last control indicia and effect transmission of its corresponding signal impulses, as disclosed in 30 the copending application of R. A. Lake, Serial No. 219,770, filed July 18, 1938. In the case of the former instrumentalities, prior to the transmission of signals for the succeeding groups of perforations, blank tape represented by the distance 35 between the perforator and the transmitter is passed through the transmitter and line time commensurate with such length of blank tape is consumed, with the consequent transmission of no intelligence.

40 An object of the present invention is the control of the position of the movable sensing mechanism by the cyclic operation of the applicator of the control indicia.

Another object of the invention is apparatus 45 wherein a loop of the strip is formed immediately upon operation of the indicia applicator which increases for each succeeding operation of the applicator when operated at a speed higher than the speed of operation of the signal transmitter.

50 A still further object of the invention is the provision of a signal storage transmitter wherein the movement of the signal storage strip relative to a control indicia sensing mechanism and the movement of the control indicia sensing mechanism relative to the strip are indeterminate of the number of code combinations stored in the storage strip.

55 Another object of the invention is the provision of a transmitter wherein the signals are

stored on a flexible storage medium and wherein relative movement of a signal sensing mechanism and the medium is determined by the existing characteristics of the strip which are variable.

5 The above and other objects of the invention are achieved by the provision either of a manually operated keyboard perforator or a signal controlled perforator operative in conjunction with a tape sensing mechanism including a plurality of sensing fingers set permutably in accordance with the perforations or control indicia in the previously prepared control strip to control the transmission of impulses symbolic of the character to be reproduced. The perforator to which the invention has been specifically applied comprises a plurality of key levers arranged to set permutably a plurality of bars which set correspondingly a plurality of interponents to control, upon the actuation of a mechanically operated punch hammer, the operation of punches arranged in a transverse row to perforate a control strip in accordance with the code allocated to a depressed key lever. Cooperating with the code punches is a feed hole 10 punch for inserting in the tape a feed hole for each operation of the punch hammer which cooperates with a tape feeding mechanism of the sensing unit to effect relative movement between the tape and the sensing mechanism.

15 The tape sensing mechanism includes the sensing fingers which are mounted in a carrier capable of oscillation about a fixed pivot away from and toward the exit channel of the keyboard perforator. According to one embodiment of the 20 invention, the movement of the carrier away from the exit tape channel of the keyboard perforator is determined by mechanism responsive to the cyclic operation of the keyboard perforator. Specifically, such movement is accomplished 25 by the provision of a pawl and ratchet mechanism operated upon each operation of the punch hammer of the perforator to position an arm and determine the extent of movement of the carrier in which the sensing fingers are mounted. 30 For each operation of the punch hammer the ratchet mechanism is operated to move the arm and allow the rotation of the carrier about its pivot an amount less than the separation between succeeding transverse rows of code 35 perforations or indicia in the control strip. In 40 commercial forms of telegraph perforators, succeeding transverse rows of perforations are separated one-tenth of an inch, and consequently each movement of the arm controlling the position of the carrier for the sensing fingers through the operation of the pawl and ratchet mechanism is less than one-tenth of an inch, which causes 45 the formation of a loop immediately that the carrier is moved away from the perforator, which 50

55 60

increases in length for each succeeding movement of the carrier.

Disablement or the feeding pawl and the return to normal of the ratchet wheel of the

5 ratchet mechanism is accomplished by a lever operated when the arm which determines the position of the carrier is in contact with the carrier upon the next succeeding operation of the punch hammer of the perforator. The extent 10 of movement of the arm is determined by the number of teeth on the ratchet wheel, for when a predetermined position is reached, further advancement of the arm is avoided by the omission of teeth on the ratchet wheel.

15 As the carrier with the sensing fingers moves about its pivot in a counterclockwise direction, the loop of tape may increase. However, for each operation of the tape feeding mechanism of the sensing unit, relative movement between the carrier and the tape will be effected, and the signal 20 perforations will be sensed and corresponding signal impulses will be transmitted.

When the arm has been moved to its fullest extent and a loop of tape between the carrier and

25 the perforator has been formed, the tape feeding mechanism of the sensing unit, which is in accordance with the disclosure of the foregoing application, operates to feed the tape through the sensing unit to permit the sensing fingers to

30 sense successively the transverse rows of perforations. When the tape between the sensing unit and the perforator becomes taut or when the loop of tape therebetween has been exhausted, the carrier with the sensing fingers will be

35 moved along the tape to bring the carrier in abutting relation to the perforator. Such operation, however, assumes idle condition of the perforator and under such circumstances the arm which determines the rotative position of the

40 carrier remains in its extreme rotative position. However, if during the period the carrier is moving along the tape or toward the perforator the perforator is reoperated, the feed and holding portions of the ratchet mechanism will be removed from the teeth of the ratchet wheel and the wheel will be restored to normal to allow the arm to engage the carrier of the sensing fingers. Of course, if the carrier abuts the perforator prior to the reoperation of the perforator, the arm remains 45 in its extended operative position until the perforator is again operated, when it will be restored in engagement with the carrier due to the restoration of the ratchet wheel to its normal or starting position.

50 Transmission of signals corresponding to the setting of the sensing fingers in accordance with the perforations in the tape is effected through the control of appropriate levers which control, in response to the rotation of a transmitting cam 55 drum, the cyclic operation of a series of electrical contacts through which the impulses identified with the code perforations are transmitted. Rotation of the transmitting cam drum is controlled by an electromagnet energized or de-energized according to the rotative condition of the carrier of the sensing fingers upon its pivot. When the carrier of the sensing fingers abuts the perforator, the electromagnet is de-energized and the transmitting cam drum is stopped.

60 According to another embodiment of the invention, the movement of the carrier of the sensing fingers about its pivot away from the tape exit channel of the perforator is determined by a spring or other elastic medium intermediate 65 the carrier and the perforator. As the tape is

advanced from the perforator through the operation of the tape feed mechanism thereof, the carrier of the sensing fingers will rotate about its pivot away from the perforator. The extent of rotation of the carrier away from the tape exit 70 channel of the perforator is determined by the characteristics of the spring or elastic medium secured to the carrier and the character of the perforated tape intermediate the sensing fingers of the carrier and the perforator. For example, 75 if the section of tape intermediate the sensing fingers and the perforator has been weakened by a large number of perforations, the carrier will be moved away from the tape exit channel of the perforator an extent materially less than the 80 extent it will be moved if such section of tape does not carry a large number of perforations which, of course, is determined by the code combinations of perforations appearing in the noted section of the tape, as determined by the operation of the perforator. Under such circumstances the advancement of the tape relative to the sensing fingers is not effected when the number of transverse rows of perforations exceeds a predetermined number. Likewise, the movement 85 of the carrier and the sensing fingers relative to the tape is not effected when the number of transverse rows of code perforations in the tape is below the number to which the tape is moved relatively to the sensing fingers. In other words, 90 relative movement between the tape and the sensing fingers is not predetermined by the number of transverse rows of code combinations of perforations included in the section of tape intermediate the sensing unit and the perforator. 95

A more complete understanding of the invention may be had from the following description, taken in conjunction with the accompanying drawings, wherein

Fig. 1 is a partial plan view of the essential 40 elements of a keyboard perforator, tape sensing unit and a signal transmitting device in accordance with one embodiment of the present invention;

Fig. 2 is a front elevational view of the structure disclosed in Fig. 1;

Fig. 3 is a view of a part of the structure disclosed in Fig. 2 but showing the sensing unit displaced from the perforator;

Fig. 4 is an end elevational view of the structure disclosed in Fig. 1;

Fig. 5 is a sectional view taken substantially along the line 5—5 of Fig. 1;

Fig. 7 is a detailed view of the mechanism utilized for effecting relative movement between the sensing unit and the perforated tape;

Fig. 8 shows another embodiment of the invention;

Fig. 9 illustrates a condition of operation of the structure shown in Fig. 8;

Fig. 10 shows a different condition of operation of the structure disclosed in Fig. 8 when the section of tape between the perforator and the sensing unit includes a small number of perforations; and

Fig. 11 is a circuit diagram of the electrical connections for the apparatus disclosed in Fig. 1.

The perforator

The present invention may be considered as including three principal units, a tape perforator 9, a tape sensing unit 10, and a transmitting 75

unit 11 (Fig. 1). Each of the several units is mounted on a base casting 12.

The perforator shown in Figs. 2 and 5 comprises a set of punches 13 movable through openings in upper and lower guide plates 14 and 15 and cooperating with a die plate 16, the plates 14 and 16 being spaced apart to form a tape guide. The punches 13 are selectively operated by an actuating member or hammer 17 and a set 10 of permutation bars or interponents 18 corresponding in number to the number of punches 13.

The hammer 17 is arranged to oscillate about a pivot 19 and is operated by an arm 20 secured to one end of a lever 21 which is pivoted on rod 15 25 (Fig. 4) journaled in ears or projections 28 and 29 formed on the outer edge of a vertical wall 30 of a casting. Lever 21 (Figs. 1 and 4) carries at its opposite end a cam roller 32 which cooperates with a cam to operate cyclically hammer 17 and effect its oscillation and correspondingly the operation of the punch pins 13.

As disclosed in Fig. 5, a sleeve 33 having a pin 34 is adjustably mounted on arm 20. Pin 34 extends loosely through an aperture in hammer 17. 25 Mounted oppositely to arm 20 is a second arm 36 which, like arm 20, carries an adjustable sleeve 37 which has an elongated pin 38 in alignment with a punch pin 39. Punch pin 39 is partially enclosed in a housing 40 which conceals a spring 30 41 arranged to subject punch 39 to spring tension and restore it to its normal position. Punch 39 is guided at its upper and lower extremities by guide plates and cooperates with a die plate 42 which is separated from the upper guide plate 35 to form a tape guide. Punch 39 serves to apply to tape 43 the feed holes in advance of the application of the code perforations by code punches 13. It is thus seen that for each operation of lever 21, the hammer 17 will be oscillated about 40 its pivot 19 and the feed hole punch 39 will be moved upwardly by pin 38 which extends through an aperture in hammer 39 to perforate the feed hole, and will be restored to the position shown in Fig. 2 by spring 41, following the restoration of arm 20 of lever 21 to the position shown 45 in Fig. 2.

The interponents or permutation elements 18 are movable back and forth over the face of hammer 17 and are adapted to be positioned in 50 different combinations with their outer ends either in operative positions beneath the corresponding punches 13 or in inoperative positions out of alignment with punches 13.

The free end of hammer 17 is upturned, which 55 portion is slotted to form guide channels for the forward end of each of the interponents 18. Upon each setting of the interponents 18, the lever 21 is oscillated and hammer 17 is moved about its pivot to form a row of perforations in 60 tape 43 through the actuation of punches 13 corresponding to the setting of the interponents 18. Also, upon the operation of arm 21, pin 38 will be actuated and feed hole punch 39 will be operated to perforate the feed hole in tape 43 in advance of the formation of the row of code 65 perforations.

Withdrawal of the feed hole punch is achieved by spring 41, whereas the withdrawal of the code punches is accomplished by a stripper bail 44 which is pivoted at 45 and which has secured thereto one end of a retractile spring 46. As disclosed, the punch pins 13 are each provided with a shoulder which cooperates with the lower surface of spring actuated stripper bail 44, so 70 that when the punches 13 are raised, stripper bail 75

44 will be moved about its pivot 45 against the action of spring 46 and without any binding action on the punches 13. When hammer 17 is returned to the position shown in Fig. 2, spring 46 is effective to withdraw the actuated punches 5 13 and restore them to their normal unactuated position.

As previously described, for each operation of lever 21, punch 39 is operated to form a feed hole adapted to be engaged by the pin teeth on a feed 10 drum 47. The latter is provided with ratchet teeth 48 to be engaged by a feed pawl 49 which is pivotally mounted on hammer 17 and which is thus reciprocated upon each operation of the latter. A star wheel 50, Fig. 8, and a knurled portion 51, Fig. 5, which facilitates manual rotation, are integrally formed and are secured to feed drum 47 by means of a nut. Formed on the outside of a bearing sleeve through which drum 47 passes is a disc 52 provided with a projection 53 20 arranged to cooperate with an arm 54 formed on feed pawl 49 and arranged with an arm 55 cooperating with a slot formed in a member 56 which is capable of being depressed to cause the withdrawal of feed pawl 49 from cooperation with 25 teeth 48 and to back step the feed drum 47 to present a previously perforated row of perforations in alignment with the code punches 13. A spring tensioned lever 57 pivoted on member 56 cooperates with star wheel 50 to back space the 30 feed drum 47 and, in turn, the tape 43.

A spring 61 connected to the lower extremity of feed pawl 49 serves to hold the feed pawl in engagement with ratchet teeth 48 of the feed drum 47 and also normally holds hammer 17 35 against the adjustable sleeve 33. When hammer 17 is moved in a clockwise direction by the action of lever 21, spring 61 is extended. Consequently, when the force on lever 21 is relieved, the energy stored in spring 61 is released and 40 hammer 17 is restored to the position shown in Fig. 2. Feed pawl 49 will also be restored and, in being so moved, will rotate feed drum 47 to advance the tape 43 to present a succeeding area thereof in alignment with the code punches 13. 45 It is thus seen that for each operation of hammer 17, feed drum 47 will be rotated and the tape 43 will be advanced step by step.

The interponents or permutation elements 18 are set in different combinations by a plurality 50 of key levers 62 suitably mounted on a pivot rod and normally held in raised position by individual springs, the levers being provided at their forward ends with key tops 63.

Beneath the key levers extend a number of 55 pairs of code bars, and since in the form shown there are five interponents 18, a corresponding number of pairs of code bars are employed. Each pair comprises a bar 64 and 65 and each pair of bars is supported adjacent to each end by a rock 60 arm 66. Each bar has its ends guided by oppositely disposed guide combs 67. These rock arms are pivotally mounted on a shaft 68 secured to a block 69 which extends transversely of the bars 64 and 65 and which is arranged with a plurality of slots, one for each rock arm 66. A similar block (not shown) is positioned adjacent the right-hand end of bars 64 and 65, as viewed in Fig. 2, which also carries a shaft 68 constituting a pivot for correspondingly shaped rock arms 70 and which also serves to limit the endwise movement of bars 64 and 65. One pair of rock arms is interposed between each two code bars comprising a pair and the bars are held in proper spaced relation by guide combs, one of which is 75

shown at 67. The rock arms 66 are substantially T-shaped or widened at their upper ends and are provided with offset lugs on opposite sides of and spaced some distance from the shaft 68. One of the lugs of each arm projects forwardly into a notch on the lower edge of the corresponding code bar 64, and its other lug projects rearwardly beneath the lower edge of the corresponding code bar 65. With this arrangement, the depression 10 of either bar of a pair of code bars rocks the arms and lifts the other code bar.

Each pair of rock arms 66 is pivoted to a longitudinally movable permutation bar 70. In the form disclosed, each bar 70 is connected to its individual lever 71 pivotally mounted on shaft 72 and having its upper end connected to its interponent 18; that is, individual to each bar 70 and its companion interponent 18 is a lever 71, so that for each movement of bar 70, corresponding movement of interponent 18 results.

Cooperating with the upper ends of levers 71, which are beveled, is a rod or roller 73 secured to a U-shaped member 74 pivoted on rod 75 and urged into cooperation with the beveled end of 25 each of the levers 71 by a spring 76. Rod 73 serves as a detent for levers 71.

Each of the key levers 62 which extends across the code bars 64-65 is arranged, when operated, to engage and depress one of the code bars of 30 each pair and thereby set the same and the permutation bars 70 and interponents 18 in a characteristic combination. Correspondingly, the punches 13 will be operated in the same characteristic combination upon the operation of hammer 17 through lever 21.

For effecting the operation of the punches 13 through the interponents 18, each key lever 62 is arranged to depress a universal bar 77 which is slidably mounted in the same manner as the 40 code bars 64-65 and also cooperates with a pair of rock arms secured to a connecting link 78 to operate under the tension of a spring 79 a bail 80 which constitutes a part of the release mechanism effective for controlling the application of 45 power to lever 21. As disclosed in Fig. 5, an arm 81 having one end fastened to an arm of bail 80 engages an adjusting screw 82 fixed in one end of pivoted arm 83 to rotate, when the connecting link 78 is shifted, arm 83 and remove the stop 50 projection from the path of spring operated latch 84 and allow application of power to the cam for operating lever 21. The form of the release mechanism may correspond to that disclosed in Patent No. 2,019,505 to A. H. Reiber of November 5, 1935, and consequently reference is made to 55 such patent for a full and complete understanding of the construction and operation of the release mechanism which is operated by the universal bar 77 upon the depression of any of the 60 key levers 62.

As disclosed in Fig. 1, an electric motor 88 has on its shaft a gear 89 which meshes with a gear 90 secured to a shaft 91 journaled in bearings 92 and 93. Also secured to shaft 91 is a gear 94 and 65 the driving portion of a friction and positive clutch 95. Through the friction and positive clutch 95 a sleeve 96 on shaft 91 is rotated. Secured to sleeve 96 is a cam 97 which cooperates with roller 32 mounted on one arm of lever 21.

70 Upon the depression of any of the key levers 62, the code bars 64-65 will be operated as will the universal bar 77 to effect the operation of the clutch release mechanism. Upon the operation of such mechanism, clutch 95 is effective, where- 75 upon power is communicated to sleeve 96 and thus

to cam 97. As cam 97 rotates, lever 21 is operated to actuate hammer 17 against the action of spring 61. It is thus seen that, for each operation of a key lever, the code bars 64-65 will be set in a characteristic combination, that the interponents 18 will be correspondingly set, that the clutch 95 will be effective and power will be applied to cam 97, and that through cam 97 the hammer 17 will be moved in a clockwise direction, as viewed in Fig. 2, to cause code punches 10 13 to perforate the tape and punch 39 to perforate the feed hole, following which the hammer 17 is restored to its normal position by the action of spring 61, which serves also to advance the feed drum 47 through the operation of feed pawl 15 49 to advance tape 43 to present the succeeding area thereof in alignment with punches 13.

Between feed drum 47 and the entrance end of the tape guide formed between the plates 14 and 16 is a member 98 which has its upper surface 20 curved to direct the tape from the feed wheel to the entrance of the tape guide in cooperation with a wire loop 99 formed to correspond with the contour of drum 47 and arranged to hold the tape firmly against the drum 47. The wire loop 99 is 25 fastened to an arm 100 which is pivoted to permit the wire loop 99 to be moved free of the feed drum 47. Positioned above the code punches 13 is a chaff or chad chute 101. A similar chad chute is provided for feed hole punch 39. 30

The sensing unit

The sensing unit includes two substantially L-shaped side members 105 and 106, each of which, as shown in Fig. 6, has a horizontally 35 projecting portion 107, a downwardly extending leg 108, and a horizontal portion 109, which are spaced by a metallic spacer and which are joined by welding or riveting.

The sensing unit which includes the frames 105 40 and 106 is pivoted, as shown in Fig. 4, on pivot pins 110 and 111 in a manner to permit free oscillation of the sensing unit. The pivot pins 110 and 111 are secured to vertically extending side members 112 and 113 (Figs. 2 and 6 respectively) 45 of a U-shaped member which is fastened to the base casting 12.

The sensing unit, as disclosed in Fig. 2, normally abuts the plates 14 and 16 of the perforator and has its entrance channel for the perforated tape in alignment with the exit channel of the tape guide formed between plates 14 and 16. Extending between and secured to the side frames 105 and 106 is a plate 115 which carries a pilot post 116 and a hinge block 117. Hinged 53 to block 117 is a tape gate 118 which has an aperture in alignment with pilot post 116 and which cooperates when in a horizontal position with a spring latch 119 which holds it in its operating position. Secured to the gate 118 by a screw is 60 pins 121 and 122, Fig. 6.

The plate 115 has its upper surface depressed or grooved to form a channel for the tape as it passes through the sensing unit and has adjacent 65 its right-hand edge, as viewed in Fig. 2, a plurality of apertures. Likewise, the right-hand edge of the gate 118 has a plurality of notches in alignment with the apertures in plate 115 when the gate is latched by latch 119.

The apertures in plate 115 receive the reduced portion of a sensing pin 125; that is, there is a sensing pin 125 individual to each of the code apertures adjacent the right-hand edge of plate 115. Inasmuch as there are five code punches 75

13 there will be a corresponding number of sensing fingers 125; for example, there will be a sensing finger or pin 125 for each of the possible perforations appearing in a transverse row of perforations.

The separation between the code punches 13 and the apertures in plate 115 when the plate 115 abuts the plates 14 and 16 corresponds to the normal spacing between successive transverse rows of perforations in tape 43. Usually the transverse rows of perforations in tape 43 are one-tenth of an inch apart and therefore the punches 13 and the apertures in plate 115 are correspondingly separated. Intermediate the 5 upper legs of the frame members 105 and 106 and in the space formed by the metallic spacer is a slidably movable member 126 which is formed with a cam groove 127, Fig. 7, and which carries on its upper extremity pins 128, 129, and 130. 10 Pins 128 and 129 are of the same length but pin 130, as shown in Fig. 7, is considerably longer than pins 128 and 129, the purpose of which will appear more clearly hereinafter. Cooperating with the cam groove 127 in member 126 is a pin 131 secured to its upper end, Fig. 4, of a cam operated arm 132. The pin 131 has an enlarged head 133, as shown in Fig. 4, to insure that the pin 131 will not be accidentally displaced from the cam groove 127.

10 As shown in Fig. 7, the downwardly projecting legs 108 of portion 107 of the side frames 105 and 106 are arranged with straight slots 134 to confine the movement of pin 131 in a vertical plane or in a straight line along or on a radii. To facilitate removal of pin 131, the lower portion of cam groove 127 and the lower portion of the slots 134 in the legs 108 of portions 107 are enlarged sufficiently to receive the head 133 of the pin 131.

As will be described hereinafter, member 126 and arm 132 are operated in timed relation. 40 Arm 132 is drawn downwardly in the slots 134 and when so drawn and due to the particular shape of cam groove 127, member 126 will be moved to the left as viewed in Figs. 1 and 6, and 45 relative movement between the sensing unit 10 and the tape 43 will be effected. Member 126 then is moved downwardly to withdraw pins 128, 129, and 130 from engagement with the feed perforations in the tape 43. Following this action, 50 arm 132 is moved upwardly and due to the camming action, member 126 is moved to the right as viewed in Figs. 1 and 6. The member 126 is thereafter elevated to cause the pins 128, 129, and 130 to engage other feed perforations in the 55 tape 43 to achieve, on a subsequent cycle, relative movement between the sensing unit 10 and the perforated tape 43.

Secured to the side members 112 and 113 are L-shaped members 138 and 139, respectively. 60 Extending between the L-shaped members 138 and 139 is a pivot shaft 147 on which is mounted a plurality of bell crank levers 148, 149, 150, 151, and 152, Fig. 6. These bell crank levers are individual to a sensing finger 125. As disclosed, 65 the sensing fingers 125 are pivotally secured to one arm of their respective bell crank lever on a center line substantially coincident with pivots 110 and 111. The bell crank levers have an extension 153, Fig. 6, cooperating with a pivotally mounted guide comb 154. Fastened to the other arm of the bell crank levers is a retractile spring 155, Fig. 3, which serves to rotate its bell crank 70 in a counterclockwise direction, as viewed in Figs. 2 and 3, and to move its sensing finger 125 vertically to sense the perforations in tape 43. If a

perforation appears opposite a sensing finger 125, it moves to its fullest extent, whereas if there is no perforation in alignment therewith, its movement is correspondingly restricted.

To facilitate assembly, each of the sensing 5 fingers 125 is provided near its lower extremity with an aperture arranged to be engaged by a pin secured near the end of the horizontally extending arm of each of the bell crank levers 148-152. A reed spring 156, Fig. 2, riveted to such arm of 10 the bell crank lever, serves to retain the lower end of the sensing finger and prevent its accidental displacement.

Guide comb 154 which is normally under the tension of a spring 151, one end of which is fastened to a spring post secured to members 112 and 113 and the other end secured to the right-hand horizontal projection of the guide comb 154, has ears 163 and 164, Fig. 6 apertured to receive pivot shaft 147 and arranged to permit the free rotation of comb 154 against the tension of its retractile spring 157. The left-hand ear 164 of guide comb 154, as viewed in Fig. 6, is secured to an arm 158, Fig. 4, of a T-shaped lever 159, Fig. 2. Arm 160 of T-lever 159 cooperates with a cam for moving cyclically comb 154 about pivot shaft 147 for the purpose later to be described. Arm 161 of T-lever 159 cooperates with a pin 162 to limit the movement of comb 154 20 against the action of spring 151. Also rotatably mounted on pivot shaft 147 is a lever 166 which has one end fastened to member 126 and which has its other end secured to a bell crank lever 167 also pivotally mounted on shaft 147 and having an arm which cooperates with a cyclically operated cam to effect reciprocational movement of member 126. Also pivotally mounted on shaft 147 is an arm 168, Figs. 1 and 6, which is secured to lever 132 and which is fastened through its arm to a lever 169 carrying a cam roller 170 30 which is held in cooperation with its cam by a spring 171 having one end secured to an arm of the lever carrying roller 170 and the other end secured to a spring post on upright 113. Secured to side frame 105, Figs. 4 and 6, is a pin 174 40 which cooperates with the insulated end of an electrical contact spring 175 which cooperates with an electrical contact spring 176 to complete the energizing circuit for a control electromagnet 177. 45

Movement of the frame including the side members 105 and 106 about the pivots 110 and 111 is under the control of mechanism operated cyclically with the operation of the perforator; 50 that is, for each operation of the perforator, mechanism is operated to allow a predetermined movement of the frame carrying the sensing fingers 125. Such movement, in accordance with a specific embodiment of the invention, is predetermined; for example, each movement as determined by the teeth on a ratchet wheel is less than the spacing of adjacent transverse rows of perforations in the tape 43.

The mechanism just referred to consists of a 55 ratchet wheel 181 rotatably mounted on a shaft 182 journaled in the side plates 112 and 113. Only a portion of the periphery of the ratchet wheel 181 carries teeth which are engaged by a feed pawl 183 and a holding pawl 184. By failing to provide teeth on the entire periphery of the ratchet wheel 181, it will be rotated only to a predetermined point or a point where the feed pawl 183 no longer engages a tooth in the 60 ratchet wheel 181. Further rotation of the 70 ratchet wheel 181. Further rotation of the 75

ratchet wheel 181 in the direction of the arrow, Fig. 6, is thus prevented.

Holding pawl 184 is pivoted on a pivot shaft 185 independently of the feed pawl 183 which is 5 pivoted to a horizontally extending member 186 and which is normally under the tension of a spring 187 to engage the teeth of the ratchet wheel 181. Holding pawl 184 has a projecting portion 188, as viewed in Fig. 2, sufficient to be 10 engaged by the pawl 183 and moved under predetermined conditions of operation against the tension of spring 189 free of the teeth of the ratchet wheel 181 and allow the restoration thereof by a restoration spring 180 to its normal or starting 15 position or the position shown in Fig. 3.

Member 186 is pivotally mounted to a plate 191 fastened to the side frame of the perforator and has attached to it one end of a spring 192, the other end of which is fastened to a fixed spring 20 post. Member 186 is slotted at 193, Fig. 2, to receive a screw 194 secured to a shouldered bushing in an aperture of arm 195 which is secured to a U-shaped frame 196, Fig. 6, which is pivotally mounted on a pivot shaft 197. Screw 194 serves 25 to clamp adjustably the shouldered bushing to member 186 at a distance from fixed pivot 190 to allow proper travel of feed pawl 183. Cooperating with the intermediate section of the U-shaped member 197 is a pin 198 secured to the end 30 of arm 20 and serving to control its operation.

Arm 20, as previously described, is a part of lever 21 which is pivoted on shaft 25 and which is operated cyclically by cam 97 secured to sleeve 96. Upon the operation of lever 21 and the upward movement of arm 20, as viewed in Fig. 2, which directional movement occurs incident the perforation of the tape in accordance with the position of the interponents 18, rod 198 will be moved free of the central section of U-shaped member 196 and spring 192 which is normally under tension, will be permitted to rock member 187 counterclockwise, as viewed in Fig. 2 and thus cause the downward movement of the feed pawl 183 sufficiently to enable it to engage the next succeeding tooth on the ratchet wheel 181 which, 45 as shown in Fig. 2, is normally under the tension of a restoration spring 180. When the perforating operation has been completed, the lever 21 is moved downwardly by the action of spring 61, whereupon the feeding pawl 49 of the tape feeding mechanism is operated to advance the tape 43 and simultaneously therewith, pin 188 engages the 50 central section of U-shaped member 196 to cause the downward movement of arm 195 and correspondingly the upward movement of pawl 183 against the tension of spring 192. Pawl 183 having engaged the next succeeding tooth of ratchet wheel 181, the latter will be rotated in the 55 direction of the arrow, Fig. 6, against its restoration spring 180. Rotation of ratchet wheel 181, it is thus seen, is timed with the operation of the feed pawl 49 and the step-by-step advancement of the tape 43 through the corresponding operation 60 of feed drum 47.

65 For each operation of the punch hammer 17, the feed pawl 183 will be operated to cause the step-by-step advancement of the ratchet wheel 181 which will be held in its advanced position by holding pawl 184. Such operation will continue until the feed pawl 183 engages the smooth 70 surface on the periphery of ratchet wheel 181, in which position the ratchet wheel will be held by the holding pawl 184 until it is moved free of the teeth of ratchet wheel 181, as will be subsequently described.

Secured to the face of ratchet wheel 181 is a pin 202. This pin lies in the path of a cam surface 203 formed on the underside of an arm 204 of a lever 205, which is pivoted on pivot pin 110 and which has a vertically extending arm 207. As ratchet wheel 181 is advanced step by step, pin 202 engages the under surface 203 of arm 204 and, due to the contour of surface 203, lever 205 will be permitted to rotate about shaft 110 and thus control the movement of the sensing unit 10 through cooperation of adjustable screw 210 with side member 105 of the frame which carries the sensing fingers 125. Adjustable screw 210 is fastened and locked in its adjusted position to a plate 211 which is pivoted to the upper end of arm 110 207 of lever 205 and has secured to it a rod 212, the lower end of which is fastened to a member 213 pivoted on a shaft 214 which is journaled in ears 215 and 216 formed in the vertical arm 207 of lever 205. As shown in Fig. 6, side member 105 25 has a projecting portion 217 which is engaged by one end of the adjustable screw 210 and, due to such cooperation and the cooperation of pin 202 with surface 203 of arm 204 of lever 205, the movement of the sensing unit 10 will be controlled. For example, when the ratchet wheel 181 is rotated, pin 202 will progress correspondingly in a circular path, and due to its engagement with surface 203 of arm 204 of lever 205, arm 207 will be permitted to rotate in a counterclockwise direction, as viewed in Fig. 6, and the frame including the sensing fingers 205 will be moved correspondingly. In order that the movement imparted to the frame by operation of the punch hammer shall be such as to move the free 30 ends of the sensing pins less than one-tenth of an inch, the spacing of adjacent transverse rows of perforations in tape 43, as previously set forth, the spacing of the teeth on ratchet wheel 181, the cooperation of pin 202 with surface 203 of arm 204 of lever 205, the movement of pawl 183, and the other variables involved in the related structure bear 35 a definite relation.

Significant is the fact that the tape is advanced from the perforator, due to the cyclic operation 45 of pin drum 47, in timed relation with the operation of the ratchet wheel 181. Consequently, when the tape is moved out of the perforator, the ratchet wheel 181 will be operated and the sensing unit will be permitted to move in a counterclockwise direction a distance dependent upon the spacing of the teeth on ratchet wheel 181 and the contour of surface 203 of arm 204 of the lever 205. However, when the feed pawl 183 engages a smooth surface of ratchet wheel 181, further rotation thereof is precluded and it will be held in its advanced position with pin 202 engaging the forward edge of surface 203 of arm 204, and the sensing unit will then be in its extreme counterclockwise position, as viewed in 50 Fig. 3.

Restoration of ratchet wheel 181 by the action 55 of its spring 180 is controlled by the removal of the feeding pawl 183 and the holding pawl 184 from engagement with the teeth in the ratchet wheel 181. To accomplish such a result, feeding pawl 183 has an arm 218 engageable by a downwardly projecting arm 219 of pivoted member 213 which, as shown in Fig. 4, is normally under tension of spring 220 having one end fastened 60 to a projection on member 207 and the other end secured to pivoted member 213. Spring 220 overcomes the weight of and the gravitational action on member 213 and its associated parts.

As was previously described, member 213 is 65

5 pivoted on shaft 214 and is connected by rod 212 to pivoted member 211, which carries adjustable screw 210 and further, that adjustable screw 210 engages projection 217. When projection 217 engages screw 210, member 211 will be rotated in a counterclockwise direction, rod 212 will be moved downwardly, and member 213 will be rotated about its shaft 214 in a counterclockwise direction, as viewed in Fig. 6 against the action 10 of spring 220. Vertically extending portion 219 of member 213 will thus be out of the path of extension 218 on feeding pawl 183 and, under such circumstances, there will be no change in the operation. However, if projection 217 is not in engagement with screw 210, member 213 will be rotated to a position where extension 219 lies in the path of extension 218 of feed pawl 183 which, upon the next cyclic operation of the punch hammer, will cause the feed pawl 183 to be moved 15 in a counterclockwise direction, as viewed in Fig. 6, and carry with it, due to projection 188, holding pawl 184 free of the teeth of ratchet wheel 181. Spring 180, having been extended due to the step-by-step operation of ratchet wheel 181, 20 will restore the ratchet wheel to its normal position or the position shown in Fig. 6. The lever 205 will, of course, be restored to the position also shown in Fig. 6.

30 The transmitting unit

Individual to each of the bell cranks 148-152 is a bell crank lever 225, Figs. 3 and 6, pivoted on a shaft 226 and held in proper position by spacing washers on shaft 226 and by a guide comb 35 227, Fig. 2.

Each bell crank lever 225 has a hook 228 at its upper end which engages the insulated upper end of a spring contact 229 and each of the latter cooperates with a contact spring 230, the pairs of contact springs being mounted upon but insulated from a supporting bar 231, Fig. 2, carried by the base casting 12. Each spring contact 229 tends to engage its associated contact spring 230 and also serves to hold a lug 232 on the horizontal arm of the corresponding bell crank lever 225 in engagement with the surface of a cam drum 233 serving as the signal transmitting cam assembly and forming a part of a cam sleeve 234 on a horizontal shaft 235 and extending over the horizontal arms of the bell crank levers 225. The cam drum 233 is provided with a helical series of recesses which, as the cam is rotated, successively pass over the lugs 232 of the bell crank levers 225. As the corresponding recess passes over one of the lugs, the associated switch contacts 229 and 230 are closed, provided the horizontal arm of the bell crank lever 225 is not restricted in its movement.

The shaft 235 is journaled in end plates 237 and 238, Fig. 4. On the sleeve 234 carrying cam or cam drum 233 is a shoulder or cam 239, Fig. 1. Sleeve 234 is splined to a driven portion 240 which constitutes a part of a positive clutch 242 through which power is communicated to sleeve 234. The driven portion 240 of the clutch has integrally formed therewith a cam surface 243 which cooperates with an extending portion 244 of a bail or clutch throwout lever 245 pivoted at 246 and functions as a clutch disengaging means. 50 The laterally extending portion 244 of bail 245 cooperates with the armature of electromagnet 177 which, when energized, withdraws the horizontal projection 244 of bail 245 free of the cam surface 243 and its horizontal projection to allow portion 240 to be shifted by spring 247 into

cooperation with the driving portion 248 of the clutch 242, which is secured to shaft 235 on which is mounted a gear 249, the latter being meshed with gear 94 and driven continuously from power supplied by motor 88. Normally, of course, spring 247 tends to move the driven portion 240 into cooperation with the driving portion 248 of the positive clutch but is prevented from such movement due to the horizontally extending portion 244 of bell crank lever 245 with the projection 10 243 on the cam surface. Consequently, the transmitting cam sleeve or drum 234 which carries the cams 233 is normally held against rotation by the stop member or bell crank lever 244 which is held in such position upon the deenergization 15 of electromagnet 177.

End plate 237 also supports one end of shaft 226, the other end of which is supported in plate 250 which, like plate 237 is secured to the base casting 12. Also as shown in Fig. 1, a spring 251 surrounds shaft 226 and is positioned between plate 237 and the first of the bell crank levers 225 to permit slight lineal movement along shaft 226.

Also secured to cam sleeve 234 are cams 252, 253, and 254. Cam 252 operates on roller 170 carried by a lever 169 to move arm 168 and, through it, arm or connecting link 132. Cam 253 operates on arm 160 of T-shaped lever 159 to rotate guide comb 154 against the tension of its spring 151 to permit movement of the bell 30 crank levers 148-152 by the action of springs 155 about pivot shaft 147 in a counterclockwise direction, as viewed in Fig. 2, and to insert the sensing fingers 125 in the perforations in the tape 43. During a subsequent portion of its cycle, cam 253 allows spring 151 to move comb 154 through which bell crank levers 148-152 are rotated about shaft 147 in a clockwise direction, as viewed in Fig. 2, and thus withdraw the sensing fingers 125 free of tape 43. As cam 254 35 rotates, it cooperates with arm 167 secured to lever 166 which, in turn, is secured to member 126 which through the action of cam 254, is reciprocated to cause the pins 128, 129, and 130 to disengage and engage successively the feed 40 perforations on tape 43.

As previously described, cooperating with each of the bell crank levers 225 is a bell crank lever 148, 149, 150, 151, and 152 which are positioned in accordance with the positions assumed by 50 their associated sensing fingers 125. If a sensing finger 125 is held depressed, which will be the position it assumes if a perforation is not aligned therewith, the free end of its bell crank lever lies in the path of the horizontal arm of its bell crank lever, such as 225. Thus, when the recess in cam 233 aligns with lug 232, the bell crank lever such as 225 is held against movement and the contacts 229 and 230 will be held open. However, if a sensing finger 125 is allowed 55 to ascend, which results from the presentation of a perforation in alignment therewith, its associated bell crank lever such as 225 is released upon the presentation of the recess of cam 233 thereto, which results in the closure of contacts 229 and 230.

As sleeve 234 rotates, the recesses in cam 233 are presented successively to the lugs 232 on the bell crank lever 225 and the contacts 229 and 230 will be operated in a manner corresponding to 70 the position of the sensing fingers 125; that is, if the sensing fingers 125 sense perforations in the tape 43, the associated bell crank levers 225 will be operated for effecting the sequential closure of contacts 229 and 230. However, if no 75

perforation is sensed, then the contacts 229 and 230 will not be allowed to close but will be held open in the position shown in Fig. 2.

The periphery of shoulder or cam 239 is formed with a recess to be entered by a roller 260, Fig. 1, carried by a spring biased arm 261 suitably pivoted to the frame. The purpose of the cam surface on cam 239 and particularly the recess therein in cooperation with roller 260 is to prevent singing or chattering of the clutch comprising driven portion 240 and driving portion 248 during periods of arrestment of the latter and to control the initial rotation of cam 233. Since spring 247 opposes the disengagement of driven clutch portion 240 from driving portion 248, a slight torsional bias may be required to establish and maintain a gap between the clutch portions after bare disengagement has occurred, it being understood that disengagement and separation of the clutch portions results solely from rotation of clutch throwout cam surface 243 against the stop member 244. Cooperation of roller 260 with the descending slope of the recess in the periphery of cam 239 provides the desired torsional bias.

Control of the initial rotation of cam 233 is important because very early in a cycle of rotation it controls one of the bell cranks 225 to impress upon the telegraph line the start impulse, the effect of which is to set in operation any telegraph printer connected to the line. If cam 233 should be permitted to be rotated far enough to initiate the start impulse before firm engagement of the clutch portions is established, as, for example, by frictional engagement of the tips of the clutch teeth, distortion of some portion of the signal combination to be transmitted is likely to result due to subsequent slipping of the clutch portions into firm engagement and accompanying variation in the velocity of cam 233. The immediate establishment of firm engagement between the clutch portions 240 and 248 may be assured by exerting upon the driven clutch portion 240 a drag sufficient to resist rotation due to frictional engagement between the teeth of the positive clutch 242. The desired drag is furnished by engagement of roller 260 with the periphery of cam 239 and particularly with the sharp ascending slope of the recess therein which roller 260 encounters substantially immediately upon the tripping of stop member 244.

Electromagnet 177 is controlled by contacts 175 and 176 which are insulatedly mounted to a frame member. Contact spring 175 carries at its free end an insulator arranged to be engaged by pin 174 mounted in the side frame 105. When the frames 105 and 106 are in the position shown in Fig. 2 with the plate 115 abutting plates 14 and 16 of the perforator, pin 174, as shown in Fig. 6, holds contact 175 free of contact 176. Instantly that the sensing unit 10 is moved counterclockwise about its pivot, which occurs upon the operation of the perforator and the advancement of the tape therefrom, pin 174 moves free of contact 175 and contacts 175 and 176 are thereupon closed to cause the energization of electromagnet 177. Electromagnet 177 is thereupon energized and through its armature, withdraws latch 244 through the operation of lever 245 from engagement with stop lug 243 to allow spring 247 to move driven portion 240 rearwardly, as viewed in Fig. 1, or to the left as viewed in Fig. 4, to engage the driving portion 248 of the positive clutch. Sleeve 234 and the cams secured thereto are thereupon rotated.

Operation

For the purpose of clarity, let it be assumed that all of the characters previously perforated in the tape 43 have been transmitted and that the sensing unit 10 has been moved to a position where its tape entrance channel is immediately adjacent the exit channel of the perforator; that is, the plate 115 of the sensing unit abuts the plates 14 and 16 of the perforator. Under such circumstances, contacts 175 and 176 are opened and electromagnet 177 is de-energized, which results in stoppage of sleeve 234.

If, under such conditions, the keyboard perforator is operated through the depression of its key levers, the permutation bars 64-65 will be set permutably. For each depression of the key lever, mechanism is operated for rendering clutch 95 effective, whereupon power is communicated to sleeve 96 and in turn to cam 97. The permuted setting of the permutation bars 64-65 causes a corresponding setting of interponents 18 through the actuation of levers 71 which, through the roller 73 by the action of spring 76, will be held in their set position and certain of the interponents 18 will be positioned beneath and in alignment with the punches 13. Cam 97 now being rotated causes the operation of lever 21, which, through adjustable sleeve 33, operates hammer 17 and through adjustable sleeve 37 and pin 38 operates punch 39 against the action of spring 41 to perforate a feed hole in tape 43. Operation of hammer 17 causes the movement of punches 13 through the interponents 18 which have been positioned to the right, as viewed in Fig. 2, to perforate tape 43 with a transverse row of perforations symbolic of the character identified with the depression of the key lever which caused the setting of the permutation bars 64 and 65. As hammer 17 moves vertically, stepping pawl 49 is brought into engagement with the next succeeding tooth of ratchet portion 48. As cam 97 continues its rotation, spring 61 becomes effective to restore hammer 17 and stepping pawl 49 to their normal position or the position shown in Figs. 2 and 3. The downward movement of stepping pawl 49 causes pin drum 47 to rotate in a counterclockwise direction, as viewed in Fig. 3, and advance the tape 43 a distance determined by the distance between succeeding teeth on ratchet 48.

Concurrently with the operation of the feed pawl 49, the U-shaped lever 39 is allowed to ascend under the action of spring 192, whereupon lever 187 is rotated about its pivot to move stepping pawl 183 downwardly to cause it to engage the next succeeding tooth on ratchet wheel 181. As the hammer 17 is restored to its normal position under the action of spring 61, U-shaped member 196 will be engaged by rod 198 and lever 187, through arm 195, will have its right-hand end, as viewed in Fig. 3, drawn downwardly, whereupon its left-hand end will be moved upwardly, carrying with it feed pawl 183 to cause the advancement of ratchet wheel 181 a distance equal to the space between its teeth, where it will be held against the action of its retractile spring 180 by holding pawl 184.

As previously described, the ratchet teeth on wheel 181 are spaced a distance less than the spacing between the rows of perforations in tape 43. Since the tape 43 is advanced by the action of feed pawl 49 through rotation of pin drum 47 and inasmuch as ratchet wheel 181, upon operation of pawl 183, is rotated an amount such that

through the cooperation of pin 202 with surface 203 of arm 204 of lever 205, arm 207 of such lever will be permitted to move about its pivot 110 a distance such that the upper end of the frame including the sensing fingers will move less than one-tenth of an inch. Engagement between projection 217 and screw 110 is maintained so that vertically extending portion 219 is out of the path of extension 218 on feed pawl 183.

10 The indicated movement of the sensing unit frees pin 174 from the insulated portion of contact spring 175 and allows the closure of contacts 175 and 176 to complete the energizing circuit for electromagnet 177. Electromagnet 177 withdraws, through pivoted lever 245, stop latch 244 from the stop lug 243 which permits driven portion 240 to slide, by the action of spring 247, into engagement with driving portion 248 of the clutch. Until the driven and driving portions of 20 the clutch are fully engaged, rotation of sleeve 234 is prevented due to the cooperation of roller 260 with cam 239. However, when the driven and driving portions 240 and 248 of the clutch are fully engaged, sleeve 234 rotates.

25 As sleeve 234 rotates, cams 233, 239, 252, 253, and 254 are rotated for achieving their respective functions. Cam 252 is effective on roller 170 to operate lever 169 through which arm 168 is operated to draw link 132 downwardly. As link 30 132 is drawn downwardly, its pin 131 cooperates with cam groove 127 to move member 126 leftwardly, as viewed in Figs. 1, 2, and 6, or away from the plates 14 and 16 it, of course, being understood that the pins 128, 129, and 130 thereof are at that instant in engagement with feed perforations in tape 43.

Due to the cam groove in member 126 a mechanical resiliency exists between the member 126 and the frame including the side members 105 and 106. Consequently, and inasmuch as the tape between the sensing unit and the perforator is taut, the side members 105 and 106 with the plate 115 move toward the exit channel of the perforator or to the right, as viewed in Fig. 2, to 40 present the sensing fingers 125 in alignment with the transverse row of perforations in tape 43 inserted as a result of the instant operation of the perforator.

Following the effectiveness of cam 252 or during the period of its effectiveness on link 132, a cam 233 becomes effective on bell crank lever 225 to allow the contacts 229 and 230 allocated to the start and stop impulses, which are normally closed, to open to transmit a start impulse for 50 effecting an operation in the receiving printer electrically connected to the transmitter previously described. Significant, of course, is the fact that the contacts 229 and 230 allocated to the start and stop impulse conditions are operated invariably at the beginning and near the end of the cycle of rotation of cam drum 233 to transmit, respectively, a start impulse and a stop impulse for achieving their allocated functions.

55 Cams 253 and 254 which, as previously described, are integral with sleeve 234 and are rotated in timed relation with cams 233, become effective for the performance of their respective function. Cam 253 operates, through lever 154 and T-shaped lever 159 having the arms 160 and 161, comb bail 154, which allows the sensing fingers 125 under the action of their individual springs 155, to assume positions in accordance with the code perforations in tape 43. If a sensing pin encounters a perforation in tape 43, its bell crank lever 148-152 moves to the right, as

viewed in Figs. 3 and 6, under the action of its spring 155 to free its bell crank lever 225. As cam sleeve 234 continues its rotation, the cam 233 for the particular bell crank lever 225 which was released by the operation of bell crank lever 148-152 will allow the closure of contacts 229 and 230 for the transmission of an impulse indicative of such setting. As the cams 233 continue through their cycle of rotation, the bell crank levers 225 will be rendered effective sequentially for the transmission of impulses dependent upon the position assumed by the sensing fingers 125 as determined by the perforations in tape 43. Following the transmission of the last impulse of the signal combination represented by the transverse row of perforations in tape 43, cam 253 becomes effective for allowing, through lever 164 and T-lever 159, spring 157 to operate comb bail 154, to rotate the bell crank levers 148-152 about their pivot 147 in a clockwise direction, as viewed in Fig. 2, and thus withdraw the sensing fingers 125 from engagement with the tape 43 preparatory to a subsequent cycle of operation.

Cam 254, as previously described, operates, through lever 167 and in turn lever 166, member 25 which carries the pins 128, 129, and 130. As cam 254 rotates, member 126 is drawn downwardly through the operation of levers 166 and 167 to free pins 128, 129, and 130 from the feed hole perforations in tape 43. Concurrently, pins 30 121 and 122 secured to the underside of reed spring 120 engage feed perforations in tape 43 and thus hold the tape and the sensing unit against relative movement.

After the pins 128, 129, and 130 have been withdrawn from the feed perforations in tape 43, cam 252 operates, through lever 169 and arm 168, link 132 upwardly to move pin 131 in the cam groove 127 of member 126 and the straight slots in the portions 107 of the side members 105 and 106. Due to the contour of cam groove 127 and because the pins 128, 129, and 130 are then free of the feed perforations in tape 43, member 126 will be moved to the right, as viewed in Fig. 2, or toward the plates 14 and 16 of the perforator. In such a position the pins 128, 129, and 130 are below other feed perforations in tape 43 and will engage such perforations upon the upward movement of member 126.

Cam 254 continues its rotation and due to its 50 contour, moves member 126 through levers 166 and 167 upwardly, causing the pins 128, 129, and 130 to enter other feed perforations in tape 43 for repeating the operation previously described upon the initial operation of the perforator. 55

As disclosed in Fig. 7, pin 130 is substantially longer than pins 128 and 129 and thus will engage the under surface of reed spring 120 and move it about its pivot to free pins 121 and 122 from the feed perforations in tape 43. Pin 130 having 60 engaged a feed perforation prior to the engagement of pins 128 and 129 with feed perforations and prior to the disengagement of pins 121 and 122 from the feed perforations, tape 43 will be held against accidental displacement and will be 65 maintained in proper alignment with the sensing fingers 125. Also, when member 126 is lowered and the pins 128 and 129 are moved free of feed perforations and prior to the engagement of pins 121 and 122 with the feed perforations corresponding to those previously engaged by pins 128 and 129, respectively, pin 130 will prevent the displacement of tape 43. Such a construction insures also that the feed perforations will not be 70 mutilated and also insures that the tape will be 75

properly spaced between successive code perforations to enable the transmission of signals corresponding to the setting of the sensing fingers 125.

- 5 The withdrawal of pins 128, 129, and 130 from the feed perforations, the upward stroke of link 132, and the reinsertion of pins 128, 129, and 130 in feed perforations are achieved by their respective cams during the transmission of the 10 code combination of impulses indicative of the setting of the sensing fingers 125.

If, during the cycle of rotation of cam sleeve 234 just described there has been no further operation of the key levers 62, the sensing unit 15 mains in abutting relation with the plates 14 and 16. Pin 174 will have operated contact 175 to cause its disengagement with contact 176. The energizing circuit for electromagnet 177 is thereupon opened, and stop latch 244 is moved 20 into the path of stop lug 243 which, when engagement is effected, the driven portion 240 against the tension of spring 247 will be moved to the right, as viewed in Fig. 4 and rotation of sleeve 234 is arrested. However, if during the 25 cycle of rotation of cam sleeve 234 another key lever 62 or other key levers 62 have been depressed, tape 43 will be advanced through the operation of pin drum 47, in which case the tape 30 43 will be drawn through the sensing unit 10 by the action of member 126 and the transverse rows of perforations in the tape 43 will be sensed successively and the impulses indicative thereof will be transmitted upon the rotation of sleeve 234.

35 For each operation of the perforator, and particularly the punch hammer 17 through lever 21, the feed pawl 183 will be operated and ratchet wheel 181 will be rotated step by step against the action of its spring 180. Correspondingly, 40 the lever 205 will be moved in a counterclockwise direction, as viewed in Fig. 6, and the sensing frame will follow it, thus maintaining projection 217 engaging screw 210, whereupon vertical extension 29 will be held out of the path 45 of extension 218 on feed pawl 183. Such operation prevails until the feed pawl 183 has engaged the last of the teeth on ratchet wheel 181 or is in engagement with the smooth periphery thereof, when further advancement of the ratchet wheel 181 is prevented. At such time, pin 202 50 will have moved along the surface 203 of arm 204 of lever 205 and allowed its rotation to permit a corresponding movement of the sensing unit. Significant, of course, is the fact that the sensing unit, under such conditions of operation, will 55 move away from the exit channel of the perforator for each operation of the perforator an amount less than the distance through which the tape is advanced by the operation of pin drum 47. 60 When the sensing unit 10 with the frames 105 and 106 has been moved to its extreme counterclockwise position, and provided the perforator is operated, the loop formed in the tape increases. Projection 207 will be in engagement with screw 65 210 and vertically extending projection 219 will remain out of the path of extension 218 of feed pawl 183.

If there is a cessation in the operation of the 70 perforator, the cam sleeve 234 with its cams continues to be rotated, due to the fact that contacts 175 and 176 remain closed, and the mechanism for advancing the tape 43 relative to the sensing fingers 125 continues. Under such conditions, the tape will be advanced step by step 75 through the sensing unit. However, when the

tape between the sensing unit 10 and the exit channel of the perforator becomes taut, the sensing unit with frames 105 and 106 will be moved step by step along the tape toward the exit channel of the perforator.

5 During the movement of the sensing unit toward the exit channel of the perforator, projection 217 no longer engages screw 210, so that member 211 is rotated in a counterclockwise direction to move vertically extending projection 10 219 of member 213 into the path of extension 218 of feed pawl 183. Should the perforator be operated under such a condition, lever 21 will be operated by cam 97 and punch hammer 17 will be actuated to allow the operation of U-shaped member 196, under the action of spring 192, to move feed pawl 183 downwardly. However, due to the engagement between the extensions 218 and 219, feed pawl 183 will be rotated in a counterclockwise direction, as viewed in Fig. 6, and 20 will carry with it, due to projection 188, holding pawl 184 free of the teeth on ratchet wheel 181. Ratchet wheel 181 is thus restored to normal by the action of spring 180 or to a position where 25 screw 210 engages projection 217 on side member 105 if entrance channel of the sensing unit is not immediately adjacent the exit channel of the perforator.

With the arrangement previously described, the movement of the sensing unit is variable as 30 compared to the advancement of the tape by the tape advancing mechanism of the perforator, which causes a loop in the tape to be formed immediately the sensing unit moves away from the exit channel of the perforator. The loop in the tape increases in size as the ratchet wheel 181 is progressively rotated until it reaches its extreme 35 rotative position when the loop in the tape is sizable. Such an operation does not necessitate the movement of the sensing unit to its extreme 40 left-hand position, as viewed in Fig. 6, before a loop in the tape is formed. Consequently, the tape is relieved of strain and the movement of the tape through the sensing unit is not determined by the number of characters in storage. 45 The tape may be moved through the sensing unit almost immediately the sensing unit is moved away from the exit channel of the punch block inasmuch as a loop in the tape forms immediately, which increases in size as the sensing head 50 moves away from the perforator.

Modification

There is shown in Figs. 8, 9, and 10 a modified form of the structure disclosed in the main embodiment of the invention. According to the arrangement disclosed particularly in Fig. 8, the movement of the sensing unit away from the perforator is under the control of a coiled spring which has one end fastened to a spring post 60 mounted in the frame of the perforator and has its other end secured to an eyelet fastened to the frame of the sensing unit. The characteristics of the spring are such as to allow the rotation of the sensing unit about its pivots an amount dependent upon the characteristics of the section of tape intermediate the sensing unit and the perforator. For example, if the noted section of tape has its area substantially perforated, then the tape is weakened materially and is incapable of moving 70 the sensing unit away from the exit channel of the perforator against the action of the coiled spring a distance equal to the distance through which it will be moved if the noted section of tape does not include a large number of perforations. 75

In other words, the extent of movement of the sensing unit is controlled by the character of the section of tape intermediate the sensing unit and the perforator.

Referring specifically to Fig. 8, the elements of the perforator disclosed have been identified with the same reference characters employed in the description of the embodiment shown in the other figures of the drawings.

The sensing unit of the embodiment shown in Fig. 8 is identical with that disclosed in the other figures of the drawings, except that its movement is not under the control of a pawl and ratchet mechanism but, as distinguished therefrom, is under the control of a spring. The transmitting unit of the embodiment shown in Fig. 8 is identical with that previously described.

As disclosed in Fig. 8, the sensing unit 10 includes side frames, one of which, namely, 105, is disclosed, which are pivotally mounted in side plates such as 112 and 113 and which are under the control of a spring 265 which has one end fastened to a spring post on the frame of the perforator and which has its other end secured to an eyelet fastened to side frame 105. The characteristics of spring 265 are such as to apply tension to sensing unit 10 and urge it in a clockwise direction, as viewed in Fig. 8.

Upon the operation of the perforator 9, as previously described, the tape 43 will be advanced step by step. At the beginning of an operation, the sensing unit 10 abuts the punch block of the perforator. Upon the initial operation of the perforator, the tape is advanced and the sensing unit 10 with its frames such as 105, is moved in a counterclockwise direction about its pivot sufficiently to allow contact springs 175 and 176 to close due to the movement of pin 174 free of the insulated end of spring 175. The closure of contact springs 175 and 176 causes the energization of electromagnet 177 and the release for rotation of cam sleeve 234 which, during its cycle of rotation, operates the cams for actuating the rectilinear feed mechanism whereby the sensing unit is moved in a clockwise direction to a position to sense the transverse row of perforations.

Movement of the sensing unit 10 in a counterclockwise direction by the advancement of tape 43 is under the control of spring 265, which normally tends to hold the sensing unit in abutting relation to the punch block of the perforator. However, upon continued operation of the perforator, additional tape 43 is advanced and the sensing unit, under the influence of spring 265, will be moved to one of its several positions such as represented by the dotted and solid line positions, Fig. 8.

The extent of movement of the sensing unit under the influence of spring 265 will depend upon the character of the section of tape intermediate the sensing unit 10 and the perforator. For example, if such section of tape contains a large number of perforations or if the area thereof is substantially perforated, then the tape is materially weakened and the spring 265 tends to draw the sensing unit toward the perforator, with the result that a loop in the tape forms almost immediately the sensing unit 10 moves away from the perforator. Such a condition is exemplified in Fig. 9 where the sensing unit 10 has moved only a short distance away from the perforator 9 due to the action of spring 265 and the fact that the section of tape intermediate the respective units contains a large number of perforations.

According to Fig. 10, the sensing unit 10 has

advanced away from the perforator 9 a distance greater than that exemplified by Fig. 9, due to the fact that the section of tape between the perforator 9 and the sensing unit 10 does not have its area substantially perforated and is therefore not weakened to the extent that it is incapable of overcoming the action of spring 266. The sensing unit 10, by the action of tape 43, will then be moved to a greater extent prior to the instant a loop is formed in the tape.

As the sensing unit continues to travel in a counterclockwise path the loop in the tape 43 increases. When such loop becomes sizable, it will fall over the back edge of the sensing unit 10, specifically, the frames 105 and 106, as shown in dotted lines in Fig. 8, and subject spring 266 to greater tension which, however, is insufficient to move its contact free of its cooperating contact on spring 267. Consequently, the circuit for electromagnet 177 will continue and the distributor cam sleeve 234 will not be arrested to stop transmission. However, when free advancement of tape 43 is prevented, as when it is held or becomes tangled, the tension of spring 266 is overcome and the circuit for electromagnet 177 is opened and the distributor cam sleeve will be arrested.

Electromagnet 177 is controlled by contact springs 175 and 266 engaging center contact spring 267. Disengagement of either contact spring 175 and 266 with contact spring 267 will open the energizing circuit of electromagnet 177. It is thus seen that spring 266 serves as a resilient back stop for the frame of the sensing unit. Under such circumstances, the operation of advancing the tape through the sensing head is not determined by any particular or predetermined number of transverse rows of perforations in tape 43.

Such operation continues; that is, the tape 43 will be drawn through the sensing unit and the transverse row of perforations therein will be sensed successively and the transmitting unit 11 will operate to transmit groups of signal impulses indicative of such rows of perforations. However, when the loop in the tape is reduced, spring 265 causes the sensing unit to move slightly in a clockwise direction toward the perforator 9 when the tape continues to be advanced through the sensing unit.

When the loop of tape has become exhausted, spring 265 aided by the tension of spring 266 moves the sensing unit further in a clockwise direction toward the perforator. However, due to the characteristic of the intervening section of tape and the characteristic of spring 265, another loop in the tape 43 will be formed. Under such circumstances the tape will be advanced through the sensing unit. These operations continue until pin 174 causes contact spring 175 to disengage contact spring 267 when the circuit of electromagnet 177 will be opened and the arrest of the distributor cam sleeve effected.

With the arrangement shown in Fig. 8, the point at which the sensing unit moves along the tape toward the perforator is indeterminate and is controlled by the character of the section of tape intermediate the sensing unit and the perforator and the action of springs 265 and 266.

While the several embodiments of the invention have been disclosed as applied to a particular type of apparatus, it is obvious that the invention is not limited to the embodiment of the particular apparatus because other modifications may be made without departing from the spirit and scope of the present invention.

What is claimed is:

1. In combination with apparatus for applying an unlimited number of permanent indicia on a record strip, apparatus for sensing the indicia including a plurality of sensing elements cooperating with the indicia and movable away from and toward said indicia applying apparatus as a unit, means controlled by said elements for transmitting signal impulses characteristic of their setting, means for effecting relative movement between the sensing elements and the strip to present successive rows of indicia to the sensing elements, and means controlled from the indicia applying apparatus for determining the movement of the sensing elements away from the indicia applying apparatus.
2. In combination with apparatus for applying an unlimited number of permanent indicia on a record strip, apparatus for sensing the indicia including a plurality of sensing elements cooperating with the indicia and movable away from and toward said indicia applying apparatus as a unit, means responsive to said elements, a plurality of electrical contacts, a rotary cam effective through the control of said sensing elements for operating said contacts sequentially as determined by the operation of said means through said sensing elements, means to advance the strip to present successive indicia to said sensing elements and for advancing said sensing elements along the strip to a point immediately adjacent the point of application of said indicia when a predetermined condition prevails in said strip, and means controlled from the indicia applying apparatus for determining one of the directional movements of the sensing elements with respect to the indicia applying apparatus.
3. In combination with a strip perforator including code punches and a feed hole punch, means for controlling the effectiveness of said punches, means for operating said code punches in accordance with the operation of said means and said feed hole punch to perforate a strip with transverse rows of perforations and feed said strip, apparatus for sensing the code perforations in said strip including a plurality of sensing fingers movable separately and as a unit, a plurality of electrical contacts through which impulses characteristic of the perforations are transmitted, means for operating said contacts sequentially in accordance with the position assumed by said sensing fingers as determined by the perforations in said strip, means cooperating with the feed holes in said strip for moving said sensing fingers along the strip to a point to sense the last row of perforations therein adjacent the exit channel of said perforator, and means responsive to the operation of the means for operating said code punches to control the movement of said sensing fingers as a unit.
4. In combination with a strip perforator including code punches and a feed hole punch, means for controlling the effectiveness of said punches, means for operating said punches in accordance with the operation of said means and said feed hole punch to perforate a strip with transverse rows of perforations and feed said strips, means for sensing the code perforations in said strip including a plurality of sensing fingers movable separately and as a unit, a plurality of electrical contacts through which impulses characteristic of the perforations are transmitted, means for operating said contacts sequentially in accordance with the position assumed by said sensing fingers as determined by the perforations
5. In combination with the feed holes in said strip, means cooperating with the feed holes in said strip for effecting relative movement between said sensing fingers and said strip, and means operated step by step for each operation of said punch operating means to control the movement of said sensing fingers as a unit away from said perforator.
6. In combination with a perforator for applying code perforations and feed perforations in a strip, a unit including a movable frame, sensing fingers in said frame for sensing code perforations in said strip, feed mechanism in said frame cooperating with the feed perforations for advancing the strip, a pivoted lever secured to each of said fingers and responsive to their position, a plurality of electrical contacts, a rotary distributor operative upon the movement of said frame to operate said contacts in accordance with the position of said levers, and a cyclically operated means effective on said movable frame for controlling the extent of its movement for each operation of said perforator.
7. In combination with a perforator for applying code perforations and feed perforations in a strip, a unit including a pivoted frame, sensing fingers in said frame for sensing code perforations, feed mechanism cooperating with the feed perforations for advancing the strip, a pivoted lever secured to each of said fingers and responsive to their position, a plurality of electrical contacts, a rotary distributor operative upon the movement of said frame about its pivot to operate said contacts in accordance with the position of said levers, and means responsive to each application of code perforations to said strip to determine the extent of movement of said frame about its pivot.
8. In combination with a perforator for applying code perforations and feed perforations in a strip, a unit including a pivoted frame, sensing fingers in said frame for sensing code perforations in said strip, feed mechanism in said frame cooperating with the feed perforations for effecting relative movement between said strip and said frame, a pivoted lever secured to each of said fingers and responsive to their positions, a plurality of electrical contacts, a rotary distributor including means to operate said feed mechanism and to actuate said contacts in accordance with the position of said levers, and means effective upon each application of code perforations in said strip to determine the extent of movement of said frame with its sensing fingers about its pivot.
9. In combination with a perforator for applying code perforations and feed perforations in a strip, a sensing unit including a frame, sensing

5 fingers in said frame for sensing the code perforations in said strip, feed mechanism cooperating with the feed perforations for effecting relative movement between said strip and said frame, 5 a pivoted lever secured to each of said fingers and responsive to their position, a plurality of electrical contacts, a rotary distributor including means to operate said feed mechanism and to 10 actuate said contacts in accordance with the position of said levers, resilient means secured to said frame and controlling the extent of its movement upon the operation of the feed mechanism whereby the point at which said strip is fed by said feed mechanism through said frame is indeterminate.

10. In a telegraph unit, a plurality of code punches and a feed hole punch, means for selectively determining the code punches to be operated, means for operating the code punches and feed hole punch to perforate correspondingly a strip, means for feeding the strip a predetermined amount for each operation of said punch operating means, means for sensing the code perforations and for transmitting signals in accordance therewith including a pivoted frame, elements in said frame responsive to the code perforations in said strip, means controlled by said elements for determining the character of the signals to be transmitted, means for effecting relative movement between the strip and said elements, and means operated cyclically with respect to the operation of said code punch operating means for controlling the rotative position 30 of said frame irrespective of the number of code perforations in said strip.

11. In a telegraph unit, a plurality of code punches and a feed hole punch, means for selectively determining the code punches to be operated, means for operating the code punches and feed hole punch to perforate correspondingly a strip, means for feeding the strip a predetermined amount for each operation for said punch operating means, means for sensing the code perforations and for transmitting signals in accordance therewith including a pivoted frame, elements in said frame responsive to the code perforations in said strip, means controlled by said elements for determining the character of the signals to be transmitted, means for effecting relative movement between the strip and said elements, means engaging said frame when in its normal position, and cyclically operated means for determining the position of said frame engaging means to control each movement of said frame about its pivot in response to the feeding of tape from said perforator an amount less than the amount the strip is advanced by the feed mechanism associated with the punches.

12. In a telegraph unit, a plurality of code punches and a feed hole punch, means for selectively determining the code punches to be operated, means for operating the code punches and feed hole punch to perforate correspondingly a strip, means for feeding the strip a predetermined amount for each operation of the punch operating means, means for sensing the code perforations and for transmitting signals in accordance therewith including a pivoted frame having two extreme positions, elements in said frame responsive to the code perforations in said strip, means controlled by said elements for determining the character of the signals to be transmitted, means for effecting relative movement 70 between the strip and said elements, and means

for controlling the movement of said frame from one of its extreme positions.

13. In a telegraph unit, means for recording signals on a strip in the form of control indicia, means for advancing the strip with respect to the recording means, mechanism adjacent the recording means for sensing the control indicia in the strip, means for advancing said strip through said mechanism and for moving said mechanism along said strip, and means for controlling the movement of the mechanism whereby the advancement of the strip through said mechanism and the movement of said mechanism along said strip is not determined by any predetermined number of control indicia in said strip. 15

14. In a telegraph unit, means for recording signals on a strip in the form of control indicia, means for advancing the strip with respect to the recording means, mechanism adjacent the recording means for sensing the control indicia in the strip, means for advancing said strip through said mechanism and for moving said mechanism along said strip, and means for controlling the movement of the mechanism in a direction away from the signal recording means whereby a loop will be formed in said strip dependent upon the character of the strip intermediate the recording means and said mechanism upon the advancement of the strip by the advancing means of the recording means. 20 25

15. In a telegraph unit, means for recording signals on a strip in the form of control indicia, means for advancing the strip with respect to the recording means, mechanism adjacent the recording means for sensing the control indicia in the strip, means for advancing said strip through said mechanism and for moving said mechanism along said strip, and means controlled from the recording means for controlling the movement of the mechanism whereby the advancement of the strip through said mechanism and the advancement of said mechanism along the strip is not determined by any predetermined number of control indicia in the strip. 30 35

16. In a telegraph unit, means for recording signals on a strip in the form of control indicia, means for advancing the strip with respect to the recording means, mechanism adjacent the recording means for sensing the control indicia in the strip, means for advancing said strip through said mechanism and for moving said mechanism along said strip, and means including a pawl and ratchet device for controlling the movement of the mechanism in a direction away from the signal recording means whereby a loop will be formed in said strip dependent upon the character of the strip intermediate the recording means and the mechanism. 40 45 50

17. In a telegraph unit, means for recording signals on a strip in the form of control indicia, means for advancing the strip with respect to the recording means, mechanism adjacent the recording means for sensing the control indicia in the strip, means for advancing said strip through said mechanism and for moving said mechanism along said strip, and means controlled from the recording means for determining that each movement of the mechanism in a direction away from the recording means will be an amount less than the amount the strip is advanced for each operation of the strip advancing means of the recording means. 60 65

18. In a telegraph unit, means for recording signals on a strip in the form of control indicia, means for advancing the strip with respect to 70 75

- the recording means, mechanism adjacent the recording means for sensing the control indicia in the strip, means for advancing said strip through said mechanism and for moving said mechanism along said strip, and means including a pawl and ratchet device controlled from the recording means for determining that each movement of the mechanism in a direction away from the recording means will be an amount less than the amount the strip is advanced for each operation of the strip advancing means of the recording means.
19. In a telegraph unit, means for recording signals on a strip in the form of control indicia, means for advancing the strip with respect to the recording means, mechanism adjacent the recording means for sensing the control indicia in the strip, means for advancing said strip through said mechanism and for moving said mechanism along said strip, and means including a pawl and ratchet device operated by the recording means for determining the extent of movement of said mechanism in a direction away from the recording means.
20. In a telegraph unit, means for recording signals on a strip in the form of control indicia, means for advancing the strip with respect to the recording means, mechanism adjacent the recording means for sensing the control indicia in the strip, means for advancing said strip through said mechanism and for moving said mechanism along said strip, and means operated by the recording means for determining the extreme position said mechanism will occupy away from the recording means where it will remain upon a cessation and operation of the recording means, and means for restoring the last mentioned means in cooperation with the mechanism upon a resumption in the operation of the recording means.
21. In a telegraph unit, means for recording signals on a strip in the form of control indicia, means for advancing the strip with respect to the recording means, mechanism adjacent the recording means for sensing the control indicia in the strip, means for advancing said strip through said mechanism and for moving said mechanism along said strip, and a resilient member attached to said mechanism normally to urge it to abut the recording means whereby the conditions under which said mechanism is moved along said strip and the strip is moved through said mechanism by its advancing means are independent of the number of signal indicia in the strip intermediate the recording means and the mechanism.
22. In a telegraph unit, means for recording signals on a strip in the form of control indicia, means for advancing the strip with respect to the recording means, mechanism adjacent the recording means for sensing the control indicia on the strip, means for advancing said strip through said mechanism and for moving said mechanism along said strip, means for transmitting signals in accordance with the operation of said mechanism, means controlling the operation of said transmitting means, means operated upon the movement of said mechanism in a direction away from said recording means to control said transmitter controlling means to effect operation of the transmitting means, and means for causing the arrest of said transmitting means in the event the mechanism moves to its extreme position away from said recording means.
23. In a telegraph unit, means for recording signals on a strip in the form of control indicia, means for advancing the strip with respect to the recording means, mechanism adjacent the recording means for sensing the control indicia on the strip, means for advancing said strip through said mechanism and for moving said mechanism along said strip, means for transmitting signals in accordance with the operation of said mechanism, an electromagnet controlling the operation of said transmitting means, and electric contacts controlled by said mechanism in either of its extreme positions for controlling the circuit of said electromagnet and the starting and stopping of the transmitting means.
24. In a telegraph unit, means for recording signals on a strip in the form of control indicia, means for advancing the strip with respect to the recording means, mechanism adjacent the recording means for sensing the control indicia on the strip, means for advancing said strip through said mechanism and for moving said mechanism along said strip, a rotary distributor for transmitting signals in accordance with the operation of said mechanism, means controlling the operation of said rotary distributor, means operated upon the movement of said mechanism in a direction away from said recording means to control said distributor controlling means to effect rotation of said distributor, and means for causing the arrest of said rotary distributor in the event the mechanism moves to its extreme position away from said recording means.
25. In a telegraph unit, means for recording signals on a strip in the form of control indicia, means for advancing the strip with respect to the recording means, mechanism adjacent the recording means for sensing the control indicia on the strip, means for advancing said strip through said mechanism and for moving said mechanism along said strip, means for transmitting signals in accordance with the operation of said mechanism, an electromagnet controlling the operation of said transmitting means, and electrical contacts one of which serves as a resilient back stop for said mechanism controlled by said mechanism in either of its extreme positions for controlling the circuit of said electromagnet and the starting and stopping of the transmitting means.
26. In combination with apparatus for applying an unlimited number of permanent indicia on a record strip, apparatus for sensing the indicia including elements cooperating with the indicia and movable with respect to said indicia applying apparatus as a unit, means controlled by said elements for transmitting signal impulses characteristic of their setting, means for effecting relative movement between the sensing elements and the strip to present successive rows of indicia to the sensing elements, and means operated in timed relation to the operation of the indicia applying apparatus for determining the movement of the sensing elements with respect to the indicia applying apparatus.
